SIMULATED DASHBOARD TOY

Herbert Roy Jaffe, Mount Vernon, N.Y., assignor to
Multiple Products Corporation, New York, N.Y., a
corporation of New York

Filed Nov. 13, 1962, Ser. No. 72,459

Term of patent 14 years

(Cl. D34—15)

Fig. 1

Fig. 2

FIGURE 1 is a front perspective view of a simulated dashboard toy showing my new design, and
FIGURE 2 is a side elevation view thereof.
The sides and rear are plain and unornamented.
I claim:
The ornamental design for a simulated dashboard toy,
as shown and described.
